UNITED STATES PATENT OFFICE.

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

Application filed October 21, 1926. Serial No. 143,082.

My invention relates to a slicing machine and particularly to a slicing machine for slicing meat, which shall be light, simple to manufacture, efficient and easy to operate. 5 One purpose of my invention is the provision of a slicing machine of the type described, wherein a particularly accurate adjustment of the gauge plate is possible. Another object is the provision of means for 10 adjusting the gauge plate to mask the otherwise exposed edge of the rotary knife, to permit ready cleaning of the gauge plate and the plate masking the knife. Another object is the provision of means for preventing 15 movement of the gauge plate when so adjusted. Another object is the provision of a meat face plate of an improved type, and means for adjusting it. Another object is the provision of means for adjusting the 20 meat carrier in relation to the opposed gauge plate. Another object is the provision of scraping means for scraping from the knife bits of the material cut.

Other objects will appear from time to 25 time in the course of the specification and claims.

I illustrate my invention more or less diagrammatically in the accompanying drawings, wherein—

30 Figure 1 is an end elevation;

Figure 2 is a plan view with parts in horizontal section;

Figure 3 is a front elevation;

Figure 4 is a section on the line 4—4 of 35 Figure 3;

Figure 5 is a detail;

Figure 6 is a section on the line 8—8 of 40 Figure 1;

Figure 7 is a section on the line 9—9 of 45 Figure 6;

Figure 8 is a diagrammatically exaggerated sectional detail view;

Figure 9 is a plan view of a modified form 50 of a meat carriage and pusher;

Figure 10 is a side elevation with parts in section;

Figure 11 is a view similar to Figure 10 55 of a variant form;

Figure 12 is a section on the line 14—14 of 60 Figure 11;

Figure 13 is a detail; and

Figure 14 is a section on the line 16—16 of 65 Figure 13.

Like parts are indicated by like symbols 70 throughout the specification and drawings.

A generally indicates any suitable base frame or member provided for example with the anti-frictional and noise deadening studs or supports A¹.

Mounted on such base member is any suitable motor means herein shown as the motor B from which projects the motor shaft B¹ on which is the driving pulley B² adapted to engage and drive the belt B³, herein shown as of triangular cross-section to engage the inclined faced channel B⁴ on the pulley B².

C is a knife supporting sleeve mounted upon the base A and including the shield port on C¹. It will be understood that the shield portion is continuous with or extends to the motor housing B and forms part of the general upwardly projecting housing or frame member C¹.

Mounted within the sleeve portion C is an inner sleeve D in which are mounted the ball bearing tracks D¹ to support the balls D² opposed to the inner tracks D³ on the knife shaft D⁴. D⁵ are locking nuts whereby to secure the knife shaft and roller bearing assembly together, the shaft D⁴ being enlarged as at D⁶ to engage the inner forward ball track D³. D⁷ is a channel pulley mounted on the shaft D⁴ adapted to receive about it the belt B³.

E is a knife disc proper secured to the shaft assembly for example by the screw E¹ and additionally secured to the pulley D⁷ for example by the screws E². The knife disc is shown as convex and is peripherally cut away or recessed on its hollow face, as at E⁴ to leave a peripheral portion E⁵ projecting somewhat forwardly from the face of the knife, the inner face of which is preferably, but not necessarily, cupped.

The sleeve C is apertured as at G, the aperture passing partially through the cylindrical interior of the sleeve. Mounted in such aperture is the locking pin G¹ cut away as at G² to permit the passage of the inner sleeve D.

Mounted on the forward face of the frame member C¹ is the fixed guard plate H which may be of any suitable material. At its left edge, as shown in Figure 3, it is arcuately cut away as at H¹ the arcuate portion penetrating or seating closely within the peripheral channel E⁴ of the knife E the axis of the knife being slightly tilted in a horizontal plane from perpendicularity to the plate, as shown in Figure 2 to bring the edge of 110

the knife forward into the position shown in such figure, generally in the plane of the guard plate H.

J is a frame or housing member upwardly projecting from the opposite end of the base A. Mounted for rotation therewithin is the control shaft J¹ upon the inner end of which is the worm J². Such shaft is controlled by the external handle J³ provided with indicating symbols as at J⁴ aligned with the opposed pointing member J⁵.

Pivoted to the vertical rock shafts J⁶ J⁷ within the housing J are the levers or pairs of levers K, K¹, at the outer end of each pair of which are pivoted the blocks or strips K², to which are secured any suitable gauge plate K³, the surface of which may be slightly convex or bowed, to conform to the cutting edge of the knife E since the active cutting portion of the knife, due to the angle at which it is set, is not in a vertical plane but is slightly bowed forward. The right edge of said gauge plate K³, as shown in Figure 3, may be arcuately formed, as at K⁴, generally concentrically with the arcuate portion H¹ of the fixed guard plate. The distance separating the opposed edges is, as shown in Figure 2, sufficient to permit the penetration therebetween of the peripheral portion E⁵ of the knife E.

Secured to the rock shaft J⁶ is a segment worm gear K⁷ which meshes with and is driven by the worm J². A tension spring K⁸ is secured at one end to a lug K⁹ on the frame J and at its opposite end to one of the pivoted blocks or strips K². This spring serves to hold the teeth in the segment K⁷ in close contact with the opposed teeth of the worm J².

Coiled around the upper part of the rock shaft J⁶ is a heavy spring K¹⁰, which is held under compression against the under side of one of the bearing lugs K¹¹ and by the collar K¹² which is secured to the rock shaft J⁶. The resulting friction acts as a brake, and tends to hold the gauge plate K³ in any position in which it may be set by the operation of the handle J³.

The support of the gauge plate by means of the parallel links K K¹ not only provides for the maintenance of the exposed face of the gauge plate in uniform angular relation to the forward face of the guard plate, and relative to the line of movement of the carriage O, below described, but also makes possible the gradual widening of the throat between the active edge of the cutter and the forward edge of the gauge plate as that throat is deepened to provide for thicker slices, thereby providing the necessary amount of clearance for the thicker slices. It will be readily understood that various well-known mechanical mountings for the gauge plate, by which uniform angular relation throughout adjustment may be main-

tained, and by which the desired widening of the throat is attained as the throat is deepened, will readily suggest themselves to the average mechanic.

It will be understood that when the gauge plate is advanced to the position shown in full line in Figure 2 it masks the cutting edge of the knife and is in what I may call neutral position. An operator can then clean the face of the gauge plate and, in order to prevent possibility of the gauge plate slipping back and exposing the edge of the knife, I provide locking means for the handle or knob J³, as shown particularly in Figures 6 and 7. Referring to such figures J¹⁰ is a recess in the frame, in which is mounted the locking ball J¹¹ normally outwardly thrust by the spring J¹². The peripheral flange J¹⁴ of the knob J³ is slotted or indented as at J¹⁵ in such fashion, or at such a location that, when the gauge plate is in neutral position, the slot G¹⁵ overlies the aperture G¹⁰ and receives the lock ball G¹¹. The locking effect is sufficient to prevent unintended rotation of the knob J³, for example by unintended contact of the arm or body.

The gauge plate K³ is illustrated as adjustable toward and away from the edge of the knife in order to conform and allow for wear of the knife or substitution of knives of somewhat differing diameter. I illustrate as means of adjustment the slots K¹⁶ in the plate through which pass screws or other suitable securing means K¹⁷ whereby the gauge plate may be laterally moved in relation to its rear supporting plate K¹⁸ to which are directly attached the strips or blocks K². K¹⁸ is a clamping washer, as shown in Figures 13 and 14.

Preferably I make the slots K¹⁶ of such size in relation to the stems of the screws K¹⁷ as to permit also vertical adjustment of the gauge plate and tilting of the gauge plate from the horizontal.

K²⁰ is any suitable top or lid member extending from end to end of the slicing machine and adapted to be secured for example by the screws K²¹ to the housing J and to the housing or frame member C¹.

L is any suitable receiving plate for receiving the material sliced by the knife and L¹ is any suitable control switch for controlling the current to the motor of the motor housing B.

M is a track herein shown as of circular cross-section mounted for example on the supports M¹ upwardly projecting from the opposite ends of the base A. The ends of the track are enclosed by the sheathes M² apertured to permit the penetration of the bolts or screws M³ headed as at M⁴ and upwardly extending through the base A, the support members M¹, the sheathes M² and into the ends of the track M. Aligned be-

neath the track M is any suitable slide or rail M⁵ herein shown as of rectangular cross-section.

Mounted for movement along the track M⁵ and the rail M⁵ is any suitable carriage or supporting member herein shown as including a body portion O and a meat engaging member O¹. Such meat engaging member includes a broad face O² slightly inclined to the horizontal and a narrower face O³ sharply inclined to the horizontal the two being generally perpendicular to each other. Downwardly depending from the body portion O is an arm or slide O⁴ with a depending finger O⁵ adapted to engage one side of the slide M⁵. Removably secured to it is a finger or enclosing member O⁶, in which is any suitable adjusting member, herein shown as the screw O⁷ controlled by the lock nut O⁸. O⁹ is a similar adjusting screw on the finger O⁵, with the lock nut O¹⁰. O¹² is a fiber bearing member, recessed in the finger O⁵ and adapted to be engaged by the adjusting screw O⁹. It will be realized that through the interplay of the opposed adjusting members, the carrier as a whole may be rotated about the circular track M in order to obtain any desired alignment with knife or guard plate or gauge plate. O¹⁶ are any suitable buffer members adapted to contact the posts M¹ at each end of the excursion of the carriage and O¹⁶ is any suitable handle for the manual movement of the carriage.

P is a meat face plate or pusher provided with a handle P¹ from which extend terminal portions P² to bushings P³ apertured to receive the guide pins or tracks P⁴ mounted on the carriage O. Forwardly extending from the handle P¹ are the supporting members P⁵ screw threaded to receive the supporting and adjusting screws P⁶ which penetrate the face plate P. P⁷ are lock nuts for preventing movement of said screws in relation to said plate.

Figures 9 and 10 illustrate a variant form of meat end plate. The carriage O, having the outwardly projecting pins or tracks P⁴ is apertured as at X to receive the pins X¹. X² indicates the handle structure of the meat end plate having the terminal apertured enlargements or bushings X³ and the intermediate bushings X⁴. The members X³ are apertured as at X⁵ to receive the screwthreaded ends X⁶ of the pins X¹. The fit is indicated as loose, in order to permit lateral adjustment of the pins in relation to the handle X². The adjustment when made is maintained by the lock nuts X⁷ X⁸ engaging the opposite sides of the handle. Mounted in the apertures X¹⁰ of the enlargements or bushings X⁴ are the supporting pins X¹¹ to the outer end of which is secured the face plate proper P. The pins X¹¹ are axially adjustable and may be locked in position for example by the lock nuts X¹².

Referring to Figures 11 and 12, which illustrate a variant form of the pins X¹ are provided with eccentric stems Z penetrating the apertures Z¹ and snugly fitting them. Z² is a lock nut and Z³ a ledge or flange on the pin X¹, whereby the pins, when adjusted, may be locked in position.

It will be realized that whereas I have illustrated and described a practical and operative device nevertheless many changes might be made without departing from the spirit of my invention, and I therefore wish my drawings and description to be taken as in a broad sense illustrative and diagrammatic rather than as limiting me to my precise showing.

The use and operation of my invention are as follows:

I provide a generally vertical, normally fixed, guard plate, arcuately cut away to permit the penetration or the exposure of the edge of the rotary knife, about a relatively restricted arc. The plane of the knife is tilted in order to bring the exposed edge generally into the plane of or close to the plane of the forward face of the guard plate. The knife is hollowed or sunk in order to permit its peripheral portion E⁵ to extend forwardly beyond the body of the knife and beyond the forward face of the guard plate. Generally aligned with the guard plate H is the adjustable gauge plate K³, controlled by the worm J², which in turn is controlled by rotation of the handle or knob J³. The gauge plate may, if desired, be slightly bowed to conform to the curvature of the exposed knife edge due to the inclination of the axis of the knife or the tilting of the plane of the knife out of parallelism with the path of movement of the carriage.

An important characteristic of my device is the tilting of the knife guard plate H and the gauge plate K³ in such fashion that their opposed edges more closely approach the carriage or the path of the carriage than do the other portions of their surface. This is illustrated in Figure 2 and is diagrammatically accentuated in Figure 10. This has for effect to permit a very close adjustment or approaching of gauge plate and guard plate and knife edge to the path of the carriage and to the forward edge of the carriage along the area which determines the thickness of the slice, namely where the gauge plate and the cutting edge cooperate. It often happens, particularly in the employment of gauge and guard plates of enameled metal, that in baking the plates during the application and hardening of the enamel, the plates are warped from the true. It is therefore extremely difficult or impossible to hold the gauge and guard plates in parallel relation with the path of the carriage, and to maintain all parts of the plate

equi-distant from the carriage path, and this limits the closeness of adjustment of knife edge to carriage. Tilting the plates, as herein shown, permits a very close adjustment of their forwardly extended edges, an adjustment which can be made regardless of minor distortions of the rest of the plate. In particular, the gauge plate, when slightly tilted, can be adjusted, when in neutral position, so that its edge masks the cutting edge of the knife, thus making it safe for the operator to clean or wipe the forward face of the gauge plate. Where it is attempted to adjust the entire plate in parallelism, it often happens that it is impossible to thrust the entire plate so far forward as completely to mask the cutting edge when the plate is in neutral position.

The gauge plate is adjustable, in response to rotation of the worm, and moves toward or away from the path of the carriage, the angular relation at which it is set being constantly maintained.

The material to be cut is placed upon the carriage O, and is moved, for the cutting excursion, from left to right as shown in Figures 2 and 3. The thickness of the slice is determined by the position of the right edge of the gauge plate K³ in relation to the exposed cutting edge of the knife, the slice passing through the aperture between knife and gauge plate and dropping upon the receiving plate L, from which it may be manually removed. With the gauge plate supported as herein shown, as the plate is moved backwardly from the cutting plane, in order to increase the thickness of the slice, the arcuate edge of the gauge plate also draws laterally away from the cutting edge, so that the throat between gauge plate is both deepened and widened.

As shown in Figure 2, the guard plate H may be adjusted toward and away from the knife, for example by means of rotation of the threaded stud bolt Q screws to the lugs Q¹ on the frame C¹ and secured by the screws Q² threaded into the stud bolt Q. Thus the guard plate can be set at any desired angle but it is preferably, as above stated, tilted back with its left edge, as shown in Figure 2, most closely approaching the line of movement of the carriage.

In the form of Figure 2, the carriage is provided with outwardly projecting guiding pins or tracks P⁴, along which slide the members P⁵ associated with the handle P¹ and the meat face plate P. The employment of a pair of positive guiding pins maintains the face plate at a constant angle in relation to the front of the carrier and the path of movement of the carrier. This angle may be adjusted by means of the screws P⁶ and the lock nuts P⁷, it being possible to tilt one or the other side of the

face plate forwardly or rearwardly, in order to obtain the desired parallelism.

In the form of Figures 9 and 10 the face plate carries its own pins or tracks X¹ which penetrate apertures X in the carriage O. In the variant form I show the tracks or pins X¹ as laterally adjustable in order to compensate for possible variations between centers of the apertures X, due to warping or misshaping during the baking of the enamel upon the carriage, when an enamel coating is applied to the metal of which it is composed. The face plate P is therein shown as fixed in relation to the supporting pins X¹¹, such pins being adjustable in relation to the handle X². Thus not only is angular relation of the plate permitted, but a very substantial range of adjustment toward and away from the cutting plane. This permits close adjustment and variation of the maximum approach of face plate to cutting plane.

It is also important that the forward face of the carrier itself be adjusted to parallelism with the cutting plane and I therefore provide the adjustment shown for example in Figure 4, whereby it is possible to tilt the carrier about the circular track M through adjustment of the opposed screws O⁷ O⁹ as shown in Figure 4.

The gauge plate is adjusted toward and away from the knife E. I have illustrated the slots K¹⁵ and the screws K¹⁶ and they are preferably of such size in relation to each other as to permit the gauge plate also to be adjusted vertically or to be tilted from the horizontal. I am thereby enabled to adjust the gauge plate and the arcuate portion thereof not only to different diameters and sizes of knife and to the same knife, as it wears down. The vertical and tilting adjustment permits the operator to adjust the arcuate portion of the gauge plate very accurately in relation to the center of rotation of the knife.

Referring to Figures 11 and 12 I have illustrated the pin X¹ as provided with an eccentric stem Z penetrating and snugly fitting the aperture Z¹ in the handle member X². The pins X¹ may be rotated about the center of rotation of the eccentric portion Z until they conform to the opposed apertures X in the frame. When so adjusted they are fixed in position by the lock nut Z².

I claim:

1. In a slicing machine, a rotary knife, a carrier, and means for guiding said carrier along a path across the face of said knife, including a pair of superposed vertically aligned tracks, and means for laterally adjusting said carrier in relation to one of said tracks, including a plurality of adjustable contact members mounted on said

- carrier and adapted to engage opposite sides of said track.
2. In a slicing machine, a rotary knife, a carrier, and means for guiding said carrier along a path across the face of said knife, including a pair of tracks, and means for laterally adjusting said carrier in relation to one of said tracks, including a plurality of adjustable contact members mounted on said carrier and adapted to engage opposite sides of said track.
3. In a slicing machine, a rotary knife, a carrier, and means for guiding said carrier along a path across the face of said knife, including a pair of superposed vertically aligned tracks, said carrier being rotatable, for adjustment about one of said tracks, and means for laterally adjusting it in relation to the other, including a plurality of adjustable contact members, mounted on said carrier and adapted to engage opposite sides of said track.
4. In a slicing machine, a rotary knife, a carrier, and means for guiding it along a path across the face of said knife, a track for said carrier comprising a bar of generally circular cross section, and means for limiting rotation of said carrier about said bar, comprising a guide rail and contact members adjustably mounted on said carrier and adapted to engage the opposite sides of said rail.
5. In a slicing machine, a rotary knife, a gauge plate positioned adjacent said knife, a carrier, and means for guiding said carrier along a path across the face of gauge plate and knife, the planes of the knife and the gauge plate being tilted slightly out of parallelism with the path of movement of the carrier.
6. In a slicing machine, a rotary knife, a gauge plate positioned adjacent said knife, a carrier, and means for guiding said carrier along a path across the face of gauge plate and knife, the planes of the knife and the gauge plate being oppositely tilted slightly out of parallelism with the path of movement of the carrier, the knife and gauge plate most closely approaching the path of the carrier adjacent their opposed edges.
7. In a slicing machine, a rotary knife, a guard plate positioned in front of said knife and cut away to permit the penetration therethrough of an arc of the cutting edge of the knife, a gauge plate terminating adjacent the exposed cutting edge of the knife, a carrier and means for guiding said carrier along a path across the face of gauge plate and guard plate, the gauge plate and guard plate being tilted slightly out of parallelism with the path of the carrier.
8. In a slicing machine, a rotary knife, a guard plate positioned in front of said knife and cut away to permit the penetration therethrough of an arc of the cutting edge of the knife, a gauge plate terminating adjacent the exposed cutting edge of the knife, a carrier and means for guiding said carrier along a path across the face of gauge plate and guard plate, the gauge plate and guard plate being tilted slightly out of parallelism with the path of the carrier.
9. In a slicing machine, a rotary knife, a gauge plate positioned adjacent said knife, a carrier, and means for guiding said carrier along a path across the face of gauge plate and knife, the planes of the knife and the gauge plate being tilted slightly out of parallelism with the path of movement of the carrier, and means for moving the gauge plate toward and away from the cutting plane of the knife.
10. In a slicing machine, a rotary knife, a gauge plate positioned adjacent said knife, a carrier, and means for guiding said carrier along a path across the face of gauge plate and knife, the planes of the knife and the gauge plate being tilted slightly out of parallelism with the path of movement of the carrier, and means for moving the gauge plate toward and away from the cutting plane of the knife, while maintaining a generally constant angular relation between its forward face and the path of the carrier.
11. In a slicing machine, a rotary knife, a carrier and means for guiding said carrier along a path across the face of said knife, a face plate upon said carrier and means for moving it toward and away from the knife along an axis generally perpendicular to the path of movement of the carrier, and guiding means therefor including a plurality of pins mounted on said carrier and adapted to penetrate said face plate.
12. In a slicing machine, a rotary knife, a carrier and means for guiding said carrier along a path across the face of the knife, a face plate upon said carrier, a handle therefor, guiding means for said face plate, adapted to guide it toward or away from the knife along an axis generally perpendicular to the path of movement of the carrier, and means for angularly adjusting said face plate.
13. In a slicing machine, a rotary knife, a carrier and means for guiding said carrier along a path across the face of the knife, a face plate upon said carrier, a handle therefor, guiding means for said face plate, adapted to guide it toward or away from the knife along an axis generally perpendicular to the path of movement of the carrier, and means for angularly adjusting said face plate, with relation to said handle and said guiding means, including a plurality of adjusting screws associated with said plate and adapted adjustably to penetrate said handle.
14. In a slicing machine, a rotary knife,

a carrier and means for guiding said carrier along a path across the face of the knife, a face plate upon said carrier, a handle therefor, guiding means for said face plate, adapted to guide it toward or away from the knife along an axis generally perpendicular to the path of movement of the carrier, and means for angularly adjusting said face plate, with relation to said handle and said guiding means, including a plurality of adjusting screws associated with said plate and adapted adjustably to penetrate said handle, and locking means associated with said screws and adapted to lock them in adjustment.

15. In a slicing machine, a rotary knife, a gauge plate and means for moving said gauge plate into and out of the cutting plane of said knife, said means including a rotary knob, and means for locking said knob when the gauge plate is in neutral position and masking the edge of said knife.

16. In a slicing machine, a rotary knife, a gauge plate and means for moving said gauge plate into and out of the cutting plane of said knife, said means including a rotary knob, and means for locking said knob when the gauge plate is in neutral position and masking the edge of said knife, including a 20 yieldingly thrust ball and an opposed slot in which it is adapted to be seated.

17. In a slicing machine, a rotary knife, a gauge plate positioned adjacent said knife, a guard plate positioned in front of said knife, a carrier, and means for guiding said carrier along a path across the face of gauge plate and guard plate, the planes of gauge and guard plates being tilted slightly out of parallelism with the path of movement of the carrier, and means for angularly adjusting the plane of the guard plate.

18. In a slicing machine, a rotary knife, a gauge plate and means for moving said gauge plate into and out of the cutting plane of said knife and means for locking said gauge plate when positioned in the cutting plane of said knife.

19. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins, and means for laterally adjusting the position of said pins.

20. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path

of movement of the carrier, and guiding means therefor, including a plurality of pins associated with said face plate structure, and means for laterally adjusting the position of said pins.

21. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins, the ends of which are screwthreaded, said screwthreaded ends being received in apertures in the meat face plate structure, the interior diameter of each said aperture being substantially larger than the diameter of the pin passing therethrough, and lock nuts upon the screwthreaded portion of said pins adapted to lock said pins in relation to said meat face plate.

22. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, supporting pins, to which said face plate is secured, forwardly projecting from said structure, and means for axially adjusting said pins in relation to said structure.

23. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier supporting pins, to which said face plate is secured, the ends of said pins being screwthreaded, said screwthreaded ends passing through apertures in said supporting structure, and adjusting lock nuts mounted on said screwthreaded portions and adapted to engage the opposite sides of said structure.

24. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins associated with said face plate structure, said pins being provided with eccentric portions penetrating said face plate structure.

25. In a slicing machine, a rotary knife, a carrier and means for guiding said carrier along a path across the face of said knife, a

- face plate upon said carrier and a supporting structure therefor, and means for moving it toward and away from the knife along an axis generally perpendicular to the path of movement of the carrier, and guiding means therefor, including a plurality of pins associated with said face plate structure, said pins being provided with eccentric portions penetrating said face plate structure, and locking means for positioning said pins, when adjusted, including a ledge on each said pin adapted to engage one side of said structure and a lock nut adapted to engage the opposite side.
- 15 26. In a slicing machine, a rotary knife, a gauge plate positioned adjacent said knife and provided with an arcuately cut away edge portion generally conforming to the periphery of said knife, means for adjusting said gauge plate in relation to said knife while maintaining the gauge plate in its normal plane, including a plurality of apertures in said gauge plate and supporting and locking members passing therethrough, the relative sizes of the apertures and said supporting members being such as to permit both vertical and horizontal movement of the adjacent portion of the gauge plate.
- 20 27. In a slicing machine, a rotary knife, a gauge plate positioned adjacent said knife and provided with an arcuately cut away edge portion generally conforming to the periphery of said knife, and means for horizontally and vertically adjusting said gauge plate in relation to said knife while maintaining the gauge plate in its normal plane.
- 25 28. In a slicing machine, a rotary knife, a gauge plate positioned adjacent such knife and provided with an arcuate edge conforming generally to the opposed arc of the cutting edge of the knife, means for holding said gauge plate in a plane generally parallel with the plane of the knife, and means for tiltably adjusting said gauge plate in such plane.
- 30 29. In a slicing machine, a rotary knife, a carrier and means for guiding said carrier along a path across the face of said knife, a plurality of guide tracks mounted on and fixed in relation to said carrier, a face plate mounted upon said tracks and movable
- therealong for movement toward and away from the cutting plane of said knife.
- 35 30. In a slicing machine, a rotary knife, a carrier and means for guiding said carrier along a path across the face of said knife, a plurality of guide tracks on said carrier, a face plate mounted upon said tracks for movement toward and away from the cutting plane of said knife and means for adjusting the plane of said face plate.
- 40 31. In a slicing machine, a rotary knife, a carrier and means for guiding said carrier along a path across the face of said knife, a face plate upon said carrier and a supporting structure therefor, and means for moving it toward and away from the knife along an axis generally perpendicular to the path of movement of the carrier, and guiding means therefor, including a plurality of pins, and means for adjusting the plane of said face plate.
- 45 32. In a slicing machine, a rotary knife, a gauge plate, a carrier and manual means for guiding the carrier along a path across the face of said knife and said gauge plate, a face plate mounted upon said carrier and manual means for moving it toward and away from the plane of the knife and gauge plate along a path generally perpendicular to the path of movement of the carrier, and guiding means for the face plate which include a plurality of pins mounted on said carrier and adapted to penetrate said face plate.
- 50 33. In a slicing machine, a rotary knife, a gauge plate, a carrier and means for guiding the carrier along a path across the face of said knife and said gauge plate, a face plate mounted upon said carrier and means for moving it toward and away from the plane of the knife and gauge plate along a path generally perpendicular to the path of movement of the carrier, and guiding means for the face plate which include a plurality of pins mounted on said carrier and adapted to penetrate said face plate.

Signed at Indianapolis, county of Marion, and State of Indiana, this 13th day of October, 1926.

WILLIAM J. CAMPBELL.

CERTIFICATE OF CORRECTION.

Patent No. 1,685,906.

Granted October 2, 1928, to

WILLIAM J. CAMPBELL.

It is hereby certified that error appears in the above numbered patent requiring correction as follows: In the drawings, sheet 3, cancel Figures 6 and 7; and that the said Letters Patent should be read with this correction therein that the same may conform to the record of the case in the Patent Office.

Signed and sealed this 6th day of May, A. D. 1930.

(Seal)

M. J. Moore,
Acting Commissioner of Patents.
